UNITED STATES PATENT OFFICE.

GEORGE N. TAYLOR, OF EAST PROVIDENCE, RHODE ISLAND, ASSIGNOR TO UNIVERSAL WINDING COMPANY, OF BOSTON, MASSACHUSETTS, A CORPORATION OF MASSACHUSETTS.

WINDING-MACHINE.

1,258,824.

Specification of Letters Patent. Patented Mar. 12, 1918.

Application filed August 9, 1916. Serial No. 114,005.

To all whom it may concern:

Be it known that I, GEORGE N. TAYLOR, a citizen of the United States, residing at East Providence, in the county of Providence, State of Rhode Island, have invented certain new and useful Improvements in Winding-Machines, of which the following is a specification.

My invention relates to improvements in winding machines and particularly to cone-winders for producing conical packages of thread, yarn or other textiles. The object of my invention is to provide a machine for winding a cone-package of improved form, having a convex base and a concave, apex end, whereby the yarn or other material is so disposed about its central core or support as to secure a more stable structure and a free and unrestricted delivery thereof in unrestricted winding the cone. To this end my improvement consists essentially in providing means for positively and progressively displacing the cone-holder in an axial direction in relation to the traverse of the thread-guide which deposits the coils of winding thereon, so that successive layers of the winding are gradually stepped forward away from the large end of the cone to cause the base to assume a convex shape while the apex end becomes correspondingly concaved.

The manner and means for carrying out the improvement are fully described in the following specification, illustrated by the accompanying drawings, in which like reference characters designate like parts. In the drawings:

Figure 1 is a front elevation of a well known type of winding machine showing my improvement applied thereto;

40 Fig. 2, an end view of the essential elements of the winding-mechanism;

Fig. 3, an enlarged, detail view of the cone-holder shifting-means, showing its connection with the main elements of the machine; and

Figs. 4 and 5, enlarged, detailed views of various operating parts of the shifting mechanism.

Referring first to Fig. 1, A designates the main frame of the winding machine in which are rotatably mounted the horizontal winding-spindle B and cam-shaft C. On the

rearward end of the spindle B is a driving-pulley D adapted to be rotatively connected therewith by suitable clutch-devices, not herein shown or described in detail, and through which the machine is operated from a driving-belt connected to any suitable source of power. Outwardly beyond the driving-pulley D is a belt-pulley E fixedly secured to the shaft or spindle B and connected by a belt e to a lower pulley E'. The pulley E' is fixed on the end of a countershaft J which carries a pinion j at its opposite end meshing with a gear c on the end of the cam-shaft C. The shaft J is journaled in a bearing in a casing J' which serves as a gear-box and oil-reservoir for the gears j, c.

Fixedly mounted on the shaft C within the sides of the frame A is the traverse-cam C', of cylindrical construction formed with a helical groove c' on its periphery. Engaging the groove c' of the cam C' is a roll or stud k depending from the under side of a slide or crosshead K to connect the latter to be reciprocated from the cam. The crosshead K is mounted to slide in a slot in the horizontal cross-piece f of a traverse-frame F which is constructed with two upright arms f', f² pivotally mounted on the cam-shaft C, in accordance with a type of construction generally employed in the present style of machine. The traverse-frame F also comprises an outer, overhanging portion F' formed with a groove or track f³, see Fig. 2, in which a traverse-bar or rod K' slides. The inner end of the traverse-bar K' is connected with the reciprocable crosshead or slide K, and at its outer end is carried an upright arm or thread-guide G provided with the usual guiding-slot or notch g.

Attached to or formed as a part of the overhanging portion F' of the frame F is a plate or back F² against which the guide G bears to direct its path of travel in relation to the winding-spindle B. As shown more particularly in Fig. 2 the guiding-face f⁴ of the traverse-frame back F² is inclined to the axis of the spindle B to adapt the guide to travel in a plane parallel with the conical surface of the cone-tube holder H which rotates with the spindle. Depending from the outer arm f' of the traverse-frame

F is an extension F^3 formed with a counter-weight f^5 at its lower end. The traverse-frame F is adapted to pivot on its bearings on the cam-shaft C to allow the thread-guide 5 G to move outward away from the axis of the winding-spindle B, as the package is built up on the cone-holder H, and the counterweighted arm F^3 acts to maintain the guide constantly bearing against the surface 10 on which the yarn is being deposited. Usually a dogging-mechanism is employed for controlling the swinging movement of the frame F to prevent the guide G from vibrating or following an irregular course 15 as it travels across the surface of the winding. As shown in Fig. 2 the present dogging-device consists of a curved sector or track M fastened to the frame A concentric with the axis of the traverse-frame F and 20 provided with a tapered groove m , see Fig. 1, with which a friction-shoe or arm m' on the frame F engages. As the dogging-device is not essential to the present invention, however, and since its construction and 25 method of operation are well known in the art, it is not herein shown or described in detail. Suffice it to state that the dog-sector or track M is hung on a stud or screw m^2 projecting from the side of the frame A and 30 this stud forms a convenient support for attaching certain parts of the cone-shifting devices of the present improvement as later more fully described.

To provide for the longitudinal shifting 35 of the cone with respect to the traverse of the thread-guide during the winding I have preferred to arrange for a sliding movement of the cone-holder H on the winding-spindle B with which it rotates. Referring particularly to Fig. 3, the cone-holder H is of conventional construction and as here shown has a bearing h on the overhanging portion of the spindle B and a second bearing h' on the outer, reduced end thereof. The outer 40 surface of the holder H is tapered to receive the paper tube or shell X, on which the cone is wound, and usually means are provided for securing the tube in place thereon. A common expedient is to employ expanding 45 dogs or arms having teeth adapted to engage the interior of the cone-tube, and arranged for withdrawal therefrom to release the tube to allow for removal of the completed packages. As this detail of the machine forms 50 no part of the present invention, it is not herein shown or described; but it might be mentioned that the tube-securing means is operated through a relative movement between the cone-holder H and a coaxial sleeve 55 N also mounted on the spindle B at the base end of the holder. As shown in Fig. 3 the sleeve N is keyed rotatively to the spindle B by means of the spline n while being adapted to slide longitudinally thereon. 60 The sleeve N is connected rotatively with

the cone-holder H by means of the radial arms or links n' , joined to lugs h^2, h^2 formed on the overhanging base end of the holder. These arms or links n' have a further function in connection with the operation of the 70 tube-securing means of the cone-holder, but as before stated, this mechanism not being essential to the operation of the cone-shifting device of the present invention it will not be specifically described. The sleeve N 75 is formed with an annular groove or slot n^4 to adapt it to be moved on the shaft or spindle B by means of a rockable lever L engaging therewith, and through the connection of the sleeve with the cone-holder the latter 80 is displaced longitudinally of the spindle as more fully explained hereinafter. From the above it will be understood that the sleeve N serves as the means for operating the cone-holder H to effect its shifting movement and 85 for the present purpose the sleeve might be constructed as an integral part of the holder, if desired.

Referring particularly to Fig. 2, the cone-holder operating-lever L is pivoted on a 90 stud l secured in an arm O fastened to the front of the main frame A of the machine. As before indicated the arm or bracket O is mounted on the outer end of the stud m^2 which secures the traverse-frame dog-sector 95 or track M in place, and a set-screw o holds it in position thereon. At its lower end the arm O is held by a screw o' fastened in the frame A and is formed with an upwardly-projecting lug o^2 . Extending through the 100 lug o^2 is a screw o^3 secured therein by a check-nut o^4 to allow for adjustment thereof. The end of the screw o^3 is adapted to contact with the side of the arm f' of the traverse-frame F to serve as an adjustable stop 105 therefor as the thread-guide G swings toward the cone-holder. It is usual to provide a stop of this nature for the traverse-frame F and the screw o' here shown is the same as generally used as a holding-means 110 therefor. It will therefore be observed that the arm O may be applied to machines of the type herein illustrated which are already in use without any alteration of the parts thereof or without drilling new screw holes 115 in their frames. For this reason my present improvement is adapted to serve as a complete attachment which can be applied to existing machines by simply replacing certain parts with others of different construction.

At the top of the lever L is a projecting stud l^2 on which is rotatably mounted a roll l^3 fitted to enter the groove n^4 in the sleeve N. An antifriction connection is thereby 125 provided between the lever and the sleeve which allows the latter to rotate freely with the spindle B while being slid thereon. Secured in the lower end of the lever L is a screw l^4 on which is rotatably mounted a 130

spherically-shaped roll l^6 . The roll l^6 engages the sides of an inclined slot p in a cam-plate P fastened to the front of the arm f' of the traverse-frame F . As shown in the detail view, Fig. 4, the cam-plate P is preferably formed of sheet-metal and constructed with a flange p' , through which it is fastened to the frame F by means of the screws p^2 , see Fig. 2. The angular slot p is formed in a rearwardly-extending tail-piece p^3 of the plate P and is inclined outwardly away from the side of the frame F with a straight portion p^4 at its end. The ball-like roll l^6 rides between the sides of the slot p while being maintained in engagement therewith without play during the rocking of the lever L , due to its spherical shape. As the traverse-frame F swings outwardly in the direction indicated by the arrow 2, Fig. 2, during the building of the cone, the cam-plate P acts to rock the lower end of the lever L away from the side of the frame A or in the direction indicated by the arrow 3, Fig. 1. The straight portion p^4 of the slot p is designed to allow the frame F to be moved outwardly a slight distance beyond the position which it assumes upon the completion of the cone without operating the lever L . This provides for moving the thread-guide G away from contact with the surface of the cone to allow for removing the latter from its holder H after it has been completed, and prevents unnecessary shifting of the cone-holder during this operation. The method of operation of the complete device is as follows:

In preparing the machine for operation the cone-tube or shell X is slipped over the outside of the holder H and secured in place thereon through the operation of any suitable fastening-devices as usually provided. The thread or yarn y is then led up from its source of supply through the slot g in the guide G and its end fastened to the tube X or holder H . The operator next swings the traverse-frame F back into operative position with the guide G bearing on the surface of the tube X and the machine is then ready for winding the cone. When the frame F is carried back to its initial position, as illustrated in Fig. 2, the cone-holder H will be shifted to the left, as viewed in Fig. 1, to the limit of its travel in this direction. Now, as the power is applied to the machine to rotate the spindle B and reciprocate the thread-guide G , at the commencement of the winding the yarn will be traversed along the holder H between the points $x-x$, Fig. 1. As the yarn builds up on the tube X it forces the thread-guide G away from the axis of the spindle B , thereby causing the traverse-frame F to swing outwardly in the direction indicated by the arrow 2, Fig. 2. This swinging movement of the frame F acts through its cam-

plate P to gradually rock the lower end of the lever L away from the frame A , or to the left as viewed in Fig. 1, and the upper end of the lever L will therefore be swung in the opposite direction or to the right. 70 As the upper end of the lever L is swung to the right it acts through its roll l^6 engaging the sleeve N to shift the cone-holder H in the same direction. In this manner as the winding progresses the cone-holder H is 75 gradually shifted along the spindle B to displace it longitudinally with respect to the fixed path of traverse of the guide G . This causes the guide to deposit the yarn in stepped back layers, progressively receding 80 from the larger end of the tube X and approaching the opposite, smaller end, so that the mass gradually assumes a convex contour at the base of the cone and a shelved, concave formation at its apex. Fig. 1 illustrates the cone-holder H at its extreme, outward position in relation to the frame A of the machine at the start of the winding with only a few layers of yarn y' deposited on the tube X ; while Fig. 3 shows the cone-holder at its extreme, inner position with the shape of the completed cone represented by the dot-and-dash lines Y . 85

It will be understood that the object of giving this concavo-convex form to the opposite ends of the cone is to provide a more stable structure of its mass, while also facilitating the delivery of the yarn in unwinding it therefrom. The convexing of the base of the cone produces a structure better able to resist rough treatment in handling and packing, while also provided for setting the cone on its base without damaging or deranging the ends of the layers thereof. The overlapping or stepping forward of the ends of the layers at the base gives a stancher structure, while the cup-shaped form at the opposite end of the cone also tends to protect the layers and add to the general stability of the whole. The 100 most important feature of improvement, however, resides in the fact that the coils of winding are prevented from overrunning or becoming displaced across the edge of the cone at its base. That is to say, the coils 110 will be prevented from slipping down over the edge of the cone or becoming pulled over in loose lengths across its base. Such overruns or loose ends interfere with the delivery of the yarn when it is drawn off over 115 the small end of the cone and frequently cause straining or breaking of the strands before the end can be freed. 120

I am aware that it is not broadly new in the art to produce a cone-package with the 125 layers disposed to form a convexed base and a concaved apex end. Heretofore, however, this method of winding the cone has only been applied to machines of the drum, or friction-drive type. The present machine is 130

distinguished from winders of the latter type in that the cone or package is rotated positively by a winding-spindle whereas in the drum- or friction-winder the cone is 5 driven through frictional contact of its surface with a drive-roll or drum. In drum-winders the speed of rotation of the cone varies with its increase in diameter and consequently the coils or turns of the winding 10 cannot be laid with uniform spacing according to a regular system. In other words, the coils are wound "open" and in a haphazard manner and a regular and systematic disposition of the windings is not attainable. 15 In contradistinction to the drum method of winding, the machine of the present invention operates with a constant and uniform synchrony between the winding-spindle and thread-guide to produce a package 20 having a regular, systematic and precise disposition of the coils or turns of the winding and is hence known as a positive or "precision" winder. As is well known, the positive type of machine is far superior to 25 that of the friction- or drum-drive style as regards the value of its product. Drum-wound cones are badly formed, soft and irregular, with loose coils, overruns, cobwebs and other defects, while positive-wound 30 packages are uniformly true and regular in shape, contain a maximum amount of material, with the windings so disposed as to provide for free and unrestricted delivery of the yarn under an even tension. It has been a simple 35 matter to adapt a drum-winder to wind the preferred form of cone herein described, only requiring that the drum be shifted along the driving-drum or roll to displace it with respect to the traverse of the thread-guide. 40 during the winding. In the present instance, however, with a machine arranged for a positive drive of the cone, various problems are met with which have herein been solved in a simple and ingenious manner. 45 The displacing of the cone with respect to the traverse is accomplished without disturbing the synchronous operation between the cone and the thread-guide, and without disorganizing or rearranging the 50 essential mechanism of the machine. Furthermore, the shifting of the cone is made consequent to a normal functioning of the general elements of the winding-mechanism and very few new elements are employed for 55 the new operation required. The added parts are of simple construction, economical to manufacture and the complete device is adapted for attachment to standard types of machines without necessitating machine operations thereon or requiring material re-fitting thereof.

Various modifications might be made in the structure and arrangement of the parts of my improved device without departing 60 from the spirit or scope of the invention;

therefore, without limiting myself to the exact embodiment herein shown and described, what I claim is:—

1. In a winding machine, the combination with a positively-rotated winding-spindle, 70 of means to traverse the yarn longitudinally of the spindle, a cone-holder mounted on the spindle to slide longitudinally thereof, and means to shift the cone-holder during the building of the cone to progressively 75 displace the layers of winding to form the cone with a convex base.

2. In a winding machine, the combination with a positively-rotated cone holder, of 80 means to traverse the yarn throughout substantially the full length of said holder with a constant extent of traverse equal to the full length of the cone, and means to effect a relative displacement between the cone-holder and yarn-traversing means during 85 the winding to cause the layers of yarn to progressively advance toward the apex end of the cone to a relatively slight extent to build the base of the package with a convex formation. 90

3. In a winding machine, the combination with a positively-rotated cone-holder, of 95 means to traverse the yarn throughout substantially the full length of the holder to build a cone having uniform layers all extending from the base of the cone to the apex end thereof, and means actuated by the growth in diameter of the winding to effect a relative displacement between the cone-holder and yarn-traversing means longitudinally of the holder to progressively displace the layers of winding to form the cone with a convex shape at its base. 100

4. In a winding machine, the combination with a positively-rotated cone-holder, of 105 means to traverse the yarn on the holder to build up uniform, superimposed layers equal in extent to the full length of the cone, and means actuated by the increase in diameter of the winding to gradually shift the cone-holder longitudinally in relation to the yarn-traversing means to progressively displace the layers of winding toward the apex end of the cone to build its base with a convex formation. 110

5. In a winding machine, the combination with a rotating winding-spindle, of 115 means to traverse the yarn longitudinally of the winding-spindle, a cone-holder connected to be positively rotated from the spindle, and means operated from the growth in diameter of the cone to displace the cone-holder longitudinally with respect to the yarn-traverse to progressively advance the layers of winding to build the cone 120 with concavo-convex ends. 125

6. In a winding machine, the combination with a rotating winding-spindle, of means to traverse the yarn longitudinally of the spindle, a cone-holder positively rotated 130

- with the spindle, and means operated from the increase in diameter of the cone to effect a relative displacement between the cone-holder and yarn-traversing means to progressively advance the layers of winding longitudinally of the holder to build the cone with concavo-convex ends.
7. In a winding machine, the combination with a positively-rotated winding-spindle, of a thread-guide connected to be traversed in synchrony with the rotation of the spindle, a cone-holder connected to be positively rotated from the spindle, and means to effect a relative displacement of the cone-holder and thread-guide longitudinally of the holder throughout the winding of the cone to cause the latter to be built up with a concavo-convex formation at its ends.
8. In a winding machine, the combination with a positively-rotated winding-spindle, of a thread-guide adapted to be traversed longitudinally of the spindle, means connected with the spindle for reciprocating the thread-guide in synchrony with its rotation, a cone-holder connected to be positively driven from the spindle, and means to displace the cone-holder longitudinally in relation to the traverse of the thread-guide to dispose the layers of winding in axial progression to build the cone with concavo-convex ends.
9. In a winding machine, the combination with a rotatable winding-spindle, of means to rotate the spindle, a thread-guide adapted to be traversed with respect to the spindle, means to reciprocate the guide, means connecting the winding-spindle and reciprocating - means to operate in synchrony, a cone-holder connected to be driven positively from the spindle, and means to effect a longitudinal displacement of the cone-holder with respect to the spindle to cause a progressive advance of the traverse of the guide in relation thereto.
10. In a winding machine, the combination with a rotating winding-spindle, of a reciprocating thread-guide, means to traverse the guide longitudinally of the spindle, driving-means connecting the spindle and guide-traversing means, a cone-holder slidably mounted on the winding-spindle to rotate therewith, and means to shift the cone-holder longitudinally of the spindle during the winding to progressively displace the layers of the cone to cause the latter to be built up with a concavo-convex formation at its ends.
11. In a winding machine, the combination with a rotatable winding-spindle and a reciprocating thread-guide, of means to rotate the spindle, means to reciprocate the guide, a cone-holder keyed to the spindle to adapt it to slide longitudinally thereof, and means to slide the cone-holder on the spin-
- dle during the winding of the cone to progressively displace the layers thereof to cause it to be built up with a concavo-convex formation at its ends.
12. In a winding machine, the combination with a positively-rotated cone-holder, of means to traverse the yarn throughout the length of the holder to build up a cone having layers of uniform length equal in extent to the full length of the cone, means to effect a separation between the cone-holder and yarn-traversing means as the cone is built up on the holder, and means operated from said separation to cause a relative displacement between the cone-holder and traversing-means longitudinally of the holder to progressively displace the layers of winding to build the cone with a convex base.
13. In a winding machine, the combination with a positively-rotated cone-holder, of means to traverse the yarn longitudinally of the holder with a uniform traverse equal in extent to the full length of the cone, said holder and yarn-traversing means arranged to recede one from the other as the winding increases in diameter, and means operated through said receding movement to displace the cone-holder longitudinally with respect to the yarn-traversing means to progressively advance the layers of winding toward the apex end of the cone to build its base with a convex formation.
14. In a winding machine, the combination with a positively-rotated cone-holder, of a thread-guide for traversing the yarn on the holder, means to reciprocate the thread-guide, means to allow the thread-guide to recede from the holder as the winding increases in diameter, and means operated from said receding movement to effect a relative displacement between the cone-holder and traversing-means longitudinally of the holder to progressively advance the layers of winding to build the cone with a concavo-convex formation at its ends.
15. In a winding machine, the combination with a rotating cone-holder, of a traverse-frame movable away from the axis of the holder, a reciprocating thread-guide carried by the traverse-frame, and means operated by the movement of the traverse-frame to shift the cone-holder longitudinally with respect to the traverse of the thread-guide to progressively displace the layers of winding to build the cone with a convex formation at its base.
16. In a winding machine, the combination with a rotating winding-spindle, of a traverse-frame movable away from the axis of the spindle, a reciprocating thread-guide carried by the traverse-frame, a cone-holder slidably mounted on the winding-spindle to rotate therewith, and means operated from the movement of the traverse-frame to slide

the cone-holder on the spindle to displace it longitudinally with respect to the traverse of the thread-guide to progressively advance the layers of winding to build the cone with 5 a convex base.

17. In a winding machine, the combination with a rotating cone-holder, of a thread-guide traversing opposite said holder, a movable traverse-frame for supporting the 10 thread-guide to adapt it to recede from the holder with the growth in the winding, a lever for shifting the cone-holder longitudinally of its axis, and means on the traverse-frame for operating the lever during the re-

15 ceding movement of the guide to displace the cone-holder in relation to the traverse of the guide to progressively advance the layers of winding to build the cone with a convex base.

20 18. In a winding machine, the combination with a rotating cone-holder, of a thread-guide reciprocating opposite said holder, a traverse-frame for supporting the guide to adapt it to recede from the holder with the 25 growth in the winding, a lever for shifting the cone-holder longitudinally of its axis, and a cam on the traverse-frame for operating the lever to displace the cone-holder as the cone is built up thereon to cause the 30 layers of winding to be progressively advanced to shape the cone with a convex base.

19. In a winding machine, the combination with a rotating cone-holder and a traversing thread-guide, of means to support the 35 guide to adapt it to recede from the holder as the cone is built up thereon, means engaging the cone-holder to shift it longitudinally of its axis during the winding, and a cam for operating said means through the 40 movement of the guide caused by the growth in diameter of the cone.

20. In a winding machine, the combination with a rotating winding-spindle, of a

cone-holder rotatable with the spindle and slidable longitudinally thereof, a traversing 45 thread-guide, a traverse-frame for supporting the guide to adapt it to move away from the cone-holder with the growth in the winding, a lever for shifting the cone-holder, and a cam-plate on the traverse-frame formed 50 with a slot engaging the lever to operate the cone-holder in the manner and for the purpose substantially as described.

21. In a winding machine, the combination with the frame thereof, of a winding- 55 spindle mounted to rotate in bearings therein, a cone-holder rotatable with the spindle and slidable longitudinally thereof, a traversing thread-guide, a traverse-frame pivoted on the machine-frame to support the 60 thread-guide to adapt it to recede from the cone-holder with the growth in the winding, a lever pivoted on the machine-frame and connected with the cone-holder to slide the latter, and a cam on the traverse-frame en- 65 gaging the lever to rock the latter during the receding movement of the guide to shift the cone-holder in the manner and for the purpose substantially as described.

22. In a winding machine, the combination with a rotating winding-spindle and a reciprocating thread-guide, of a traverse-frame for supporting the guide to recede from the spindle with the growth in the 70 winding, a cone-holder rotatable with the 75 spindle and slidable thereon, a sleeve connected to the cone-holder to slide the latter, a pivoted lever, a roll on the lever engaging an annular groove in the sleeve, a cam-plate on the traverse-frame formed with a slot, 80 and a roll on the opposite end of the lever engaging the slot in the cam-plate to move the lever to shift the cone-holder.

In testimony whereof I affix my signature.

GEORGE N. TAYLOR.
